United States Patent Office

Des. 198,415
Patented June 9, 1964

198,415

BOAT

Thomas Benjamin Shuler, 1615 Cline St., Bossier City, La.

Filed Apr. 17, 1963, Ser. No. 74,489

Term of patent 14 years

(Cl. D71—1)

Fig. 1.

Fig. 2.

Fig. 3.

Fig. 4.

Fig. 5.

I claim:

The ornamental design for a boat, substantially as shown.
